UNITED STATES PATENT OFFICE.

SYLVIE MONTEGUT, OF PARIS, FRANCE, ASSIGNOR TO BOUE SOEURS, INC., A CORPORATION OF NEW YORK.

DESIGN FOR A FACE-POWDER BOX.

Application filed November 2, 1923. Serial No. 7,650. Term of patent 14 years.

To all whom it may concern:

Be it known that I, SYLVIE MONTEGUT, a citizen of France, and a resident of Paris, Department of Seine-et-Oise, France, have invented a new, original, and ornamental Design for Face-Powder Box, of which the following is a specification, reference being had to the accompanying drawing, forming a part thereof.

Figure 1 is a plan view looking down on the top of a face powder box embodying my new design, and

I claim:

The ornamental design for a face powder box, as shown.

SYLVIE MONTEGUT.
